By his Attorney
David W. Gardner

UNITED STATES PATENT OFFICE.

GEORGE W. BECHTOLD, OF JERSEY CITY, NEW JERSEY.

AUTOMATIC FIRE-EXTINGUISHER.

992,741.

Specification of Letters Patent. Patented May 16, 1911.

Application filed April 1, 1910. Serial No. 552,926.

To all whom it may concern:

Be it known that I, GEORGE W. BECHTOLD, a citizen of the United States, residing in Jersey City, Hudson county, and State of New Jersey, have invented certain new and useful Improvements in Automatic Fire-Extinguishers, of which the following is a specification.

My improvements relate to automatic fire extinguishers in which the valve is held to its seat by a strut consisting of united lever arms interposed between it and a bearing in axial line with the valve, said lever arms being held together by fusible material which melts and releases the lever arms at a relatively low prescribed temperature. These united lever arms have to withstand variations in pressure exerted against the valve, such variations tending constantly to disintegrate the fusible material by which the arms are held together, resulting sometime in premature release of the valve and consequent damage by water.

It is the object of my invention to strengthen the union between the lever arms to enable them to resist variations or excess of pressure exerted upon and by the valve, without decreasing the sensitiveness of the releasing device to heat, thus guarding against premature or accidental flooding.

The invention consists in the specific construction and arrangement of parts herein-after described and claimed, a distinguishing feature being the use of a bifurcated key which straddles a spine on one lever arm to which the key is soldered, and which bears against a return bend on the other lever arm, whereby the lever arms are positively locked together until the bifurcated key is released by the melting of the fusible material.

In the accompanying drawings, Figure 1, is a side elevation of an automatic fire sprinkler provided with my improved strut or valve-support; Fig. 2, a top view of same; Fig. 3, a central vertical section; Fig. 4, a bottom view; Fig. 5, a transverse section upon plane of the line 5—5—Fig. 2; Figs. 6 and 7, detail views of the return bend lever arm; Figs. 8 and 9, detail views of the key lever arm; Fig. 10, an isometrical view of the key.

The valve seat, posts, deflector, &c., are of well known construction, my invention relating only to the "strut" or valve support S, interposed between the valve v, and the

opposed bearing b. The strut or valve support S, consists of the two lever arms s, and s', the key k, and the fusible material f; and by the term "fusible material" as herein used, I mean to designate, any metal, solder alloy, composition or substance adaptable to the purpose and fusible at a sufficiently low temperature. The longer lever arm s, is formed with the bearing toe s², at its inner extremity and at its outer extremity with the return bend s³. The shorter lever arm s', is formed at its inner end with the bearing toe s⁴, and with the central longitudinal spine s⁵, on its outer side. It is also formed with the flat key seat s⁶, having the shoulder s⁷.

The contacting surfaces of the lever arms s, s', are soldered together, in the usual way and the key k, is soldered to the seat s⁶, and shoulder s⁷, and reinforced thereon by external masses of solder f, or other fusible substance applied on both sides of the spine s⁵, and over the bifurcated end of the key k, which latter is formed with the slot k', permitting it to straddle the spine s⁵, of the lever arm s'. Thus as indicated in Fig. 5, fusible matter f, is used to unite the lever arms between the contacting surfaces as well as on the bifurcated end of the key k, and the adjacent sides of the spine s⁵. The soldering of the key k, to its seat s⁶, s⁷, and its reinforcement thereon by the solder applied to its bifurcated ends and to the sides of the spine s⁵, holds the other end k², of the key 90 in rigid contact with the return bend s³, of the longer lever arm s, until such time as the temperature is sufficiently high to melt the fusible material. Thus my bifurcated key k, performs an important function in that it 95 positively locks the lever arms together at ordinary temperatures, or below a prescribed degree of heat, thereby compensating for or neutralizing and resisting excess or variations of pressure exerted upon and 100 by the valve v.

What I claim as my invention and desire to secure by Letters Patent is,

In an automatic fire extinguisher, a valve support comprising two lever arms having 105 bearings arranged in an axial line, said lever arms extended radially and united beyond the axial line of said bearings, one lever arm being longer than the other and formed with a bearing toe at its inner extremity and a return bend at its outer extremity to form a rest for a key, the shorter

lever arm being formed at its inner extremity with a toe, with a central longitudinal spine on its outer side and with a flat key seat and a shoulder adjacent thereto, and 5 a key held between the end of the upper arm and the said shoulder and engaged horizontally between said key seat and the rest on the return bend, said key being soldered to said seat and having a slot straddling

said spine and engaging said shoulder, and 10 fusible material uniting the key and seat and reinforcing said seat and key to hold the outer end of the key in rigid contact with the rest on the return bend.

GEORGE W. BECHTOLD.
